UNITED STATES PATENT OFFICE

2,062,515

TREMOLO DEVICE

Frederick A. Hoschke, South Haven, Mich.; Wilhelmina Hoschke executrix of said Frederick A. Hoschke, deceased

Application February 26, 1935, Serial No. 8,384

5 Claims. (Cl. 181—27)

My invention relates to improvements in tremolo devices i. e., for producing a change in intensity in the sounds coming from loud speakers, such as those of the dynamic or other types, and it consists in the combinations, constructions and arrangements herein described and claimed.

An object of my invention is to provide a device which is primarily designed to be used in connection with my improved musical instrument, as disclosed in my prior application, Serial No. 719,396, filed April 6, 1934, although it can be used in connection with any loud speaker where tremolo effects are desired.

A further object is to provide a tremolo device which may be operated by the usual organ stop and which consists of relatively simple mechanism as compared with other tremolo devices for organs.

A further object is to provide a tremolo device which puts an air load on the cone of the loud speaker so as to make the latter act more like a true piston than it does if the speaker were delivering into the open air. The means for accomplishing this will be fully disclosed hereinafter.

Other objects and advantages will appear in the following specification and the novel features of the invention will be particularly pointed out in the appended claims.

My invention is illustrated in the accompanying drawing forming part of this application, in which:

Figure 1 is a sectional view of the apparatus, the loud speaker being shown in elevation.

Figure 2 is a view showing a stop which controls the circuit of an electric motor, and,

Figure 3 is a fragmentary sectional view showing a modified form of mechanism.

The tremolo device may be located in any suitable position. In practice I prefer to locate it within the container that may be used for the organ bench, the tone being projected forwardly (to the rear of the organist) into the room or hall in which the device is placed. In Fig. 1 a portion of the framework of the bench is shown at 4.

Underneath this is a conventional loud speaker 5 having a cone 6, the loud speaker being mounted on a shelf 7. A partition 8 is provided which extends from the member 4 to a bottom member 9 of the framework or housing, and this partition is provided with an opening 10. The front 11 of the cone fits tightly against the partition 8, the latter being preferably made of some sound-absorbing material, such as cellular wall board.

Centrally disposed with respect to the cone and the opening 10, is a flare-horn 12. In the pres-

ent instance this flare-horn is shown as a hollow truncated cone. The interior surface of this cone is roughened, and to this end I preferably coat the interior of the flare-horn 12 with glue, to which is applied coarse sawdust, so as to give the interior of the flare-horn a coating 13, which is rough.

Within the flare-horn is disposed a transverse shaft 14, which is journaled at its ends in bearings 15 in the sides of the flare-horn, and is provided with a pulley 16 which is rigidly secured thereto. The shaft 14 also bears fan blades 17 which are rigidly secured to the shaft. In the present instance I have shown two blades. Any suitable number may be used. A belt 18 passes over the pulley 16, thence through openings 19 in the flare-horn, and around the pulley 20, on an electric motor 21 carried on the base 9.

Connections 22 and 23 respectively lead from the motor 21 to a source of current, not shown. The conductor 23, as shown in Fig. 2, is connected to the source of current through the means of a switch S. A conventional organ stop 24 is provided which can be pulled out so as to close the switch and thus complete the circuit through the motor, or to open the switch, when it is pushed in, to de-energize the motor.

A grille cloth 25 is disposed at the larger end of the flare-horn covering an opening 26, while a smaller grille cloth 27 covers an opening 28 in the rear of the loud speaker.

From the foregoing description of the various parts of the device, the operation thereof may be readily understood. When it is desired to produce a tremolo effect the stop 24 is pulled outwardly, thus closing the circuit to the motor. The latter, through the medium of the belt 18 and the pulley 16 revolves the blades 17. The roughened surface of the interior of the flare-horn 12 tends, together with the grille cloth 25, to provide an air resistance column in front of the loud speaker. With the fan in operation there is a variation in the pressure or air load on the loud speaker cone, and this variation of pressure causes an effective tremolo which is made much more effective by the roughening of the interior surface of the flare-horn than if this interior surface were smooth.

My invention contemplates the use of a pneumatic motor instead of an electric motor when it is desired to do so. In Fig. 3, I have shown, diagrammatically, a pneumatic motor at 29, having a supply pipe 30 leading to any suitable source of air pressure, not shown.

While I have referred to the apparatus as being

used in combination with a bench it will be understood that the tremolo device may be placed in any suitable position without departing from the spirit of this invention.

5 I am aware that it is not broadly new to employ a fan for producing a tremolo, but I am not aware of any device heretofore in which a fan is employed in connection with a loud speaker where such fan is enclosed in an air column within a 10 flare-horn having its inner surface roughened to increase the air load.

I claim:

1. A tremolo device for loud speakers having a cone, comprising a flare-horn for conducting the 15 sound from the cone, a grille cloth covering one end of said flare-horn, a fan disposed within the flare-horn between the grille cloth and the cone, and means for actuating the fan at will.

2. A tremolo device for loud speakers having 20 a cone, comprising a flare-horn for conducting the sound from the cone, said flare-horn having a rough interior surface, a grille cloth covering one end of said flare-horn, a fan disposed within the flare-horn between the grille cloth and the cone, 25 and means for actuating the fan at will.

3. A tremolo device for loud speakers having a cone, comprising a sound absorbing partition having an opening arranged to register with the end of the cone, a flare-horn having one end disposed against said sound absorbing partition, a 30 grille cloth covering the opposite end of the flare-

horn, a fan disposed within the flare-horn between the grille cloth and the cone, and means for actuating the fan at will.

4. A tremolo device for loud speakers having a cone, comprising a flare-horn for conducting 5 the sound from the cone, said flare-horn having openings in its walls, a grille cloth covering one end of said flare-horn, a fan disposed within the flare-horn between the grille cloth and the cone, a motor disposed outside of the flare-horn, a belt 10 for said motor extending through the openings in the flare-horn, a shaft for rotatably mounting the fan, and a pulley disposed on the shaft and driven by the belt from the motor.

5. A tremolo device for loud speakers having 15 a cone, comprising a flare-horn for conducting the sound from the cone, said flare-horn having openings in its walls, a grille cloth covering one end of said flare-horn, a shaft rotatably mounted 20 in the walls of the flare-horn and extending therethrough, a fan carried by said shaft within the flare-horn between the grille cloth and the cone, a pulley carried by the shaft, a belt for said pulley extending through the openings in the 25 flare-horn, an electric motor disposed outside of the flare-horn for driving the belt, electrical connections for actuating the motor including a switch, and an organ stop for opening and closing the switch at will.

30

FREDERICK A. HOSCHKE.
